(57)

CLAIM

The ornamental design for a compressor, as shown and described.

DESCRIPTION

FIG. 1 is a front perspective view of a compressor;
FIG. 2 is a rear perspective view thereof;
FIG. 3 is a left side view thereof;
FIG. 4 is a front view thereof;
FIG. 5 is a right side view thereof;
FIG. 6 is a rear view thereof; and,
FIG. 7 is a top view thereof.

(Continued)

The broken lines depict portions of the compressor that form no part of the claimed design.
